The ornamental design for a bottle, as shown and described.

DESCRIPTION

FIG. 1 shows a front view of the bottle, the rear view of the bottle being identical to the front view,

FIG. 2 shows a side view of the bottle (viewed at 90° to the front view),

FIG. 3 shows a top view; and,

FIG. 4 shows a bottom view.

The characteristic feature of the design resides in the fern leaf pattern applied to the body and neck of the bottle.
